UNITED STATES PATENT OFFICE.

LEROY S. PFOUTS, OF CANTON, OHIO, ASSIGNOR TO THE MILLER PASTEURIZING MACHINE COMPANY, OF CANTON, OHIO, A CORPORATION OF NEW JERSEY.

DESIGN FOR A BASE FOR LIQUID-TREATING APPARATUS.

43,579.

Specification for Design.

Patented Feb. 18, 1913.

Application filed November 19, 1912. Serial No. 732,376. Term of patent 14 years.

To all whom it may concern:

Be it known that I, LEROY S. PFOUTS, a citizen of the United States, residing at Canton, in the county of Stark and State of Ohio, have invented a new and original and ornamental Design for a Base for Liquid-Treating Apparatus, of which the following is a specification, reference being had to the accompanying drawing, forming a part hereof.

In the drawing: Figure 1 is a side eleva-

tion of a base for liquid treating apparatus showing my new design. Fig. 2 is a top plan view thereof.

I claim:—

An ornamental design for a base for liquid treating apparatus as shown.

LEROY S. PFOUTS.
